The ornamental design for pool cleaner housing with curvilinear contour line, as shown and described.

DESCRIPTION

FIG. 1 is a top perspective view of one embodiment of the pool cleaner housing showing new design;

FIG. 2 is a top plan view shown on a greatly enlarged scale thereof;

FIG. 3 is a side elevation view shown on a greatly enlarged scale, it being understood that the opposite side is a mirror image thereof;

FIG. 4 is a front elevational view shown on a greatly enlarged scale, it being understood that the rear side is a mirror image thereof;

FIG. 5 is a bottom plan view shown on a greatly enlarged scale thereof;

FIG. 6 is a perspective view similar to that of FIG. 1 showing the housing installed on a pool cleaner body;

FIG. 7 is a top perspective view of a second embodiment of the pool cleaner housing of my invention;

FIG. 8 is a top plan view of the cleaner of FIG. 7;

FIG. 9 is an side elevational view of the housing of FIG. 7 it being understood that the opposed side is a mirror image thereof;

FIG. 10 is a front elevational view of the cleaner of FIG. 7 it being understood that the rear side is a mirror image thereof;

FIG. 11 is a bottom plan view of the cleaner of FIG. 7;

FIG. 12 is a top perspective view of the cleaner of FIG. 7 shown in position on a pool cleaner body;

FIG. 13 is a top perspective view of a third embodiment of the pool cleaner housing of my invention;

FIG. 14 is a top plan view of the cleaner of FIG. 13;

FIG. 15 is a side elevational view of the housing of FIG. 13 it being understood that the opposite side is a mirror image thereof;

FIG. 16 is a front elevational view of the cleaner of FIG. 13 it being understood that the rear side is a mirror image thereof;

FIG. 17 is a bottom plan view of the cleaner of FIG. 13;

FIG. 18 is a top perspective view of the cleaner of FIG. 13 shown mounted on a pool cleaner body;

FIG. 19 is a top perspective view of a third embodiment of the pool cleaner housing of my invention;

FIG. 20 is a top plan view of the cleaner of FIG. 19;

FIG. 21 is a side elevational view of the cleaner of FIG. 19 it being understood that the opposite side is a mirror image thereof;

FIG. 22 is a front elevational view of the cleaner of FIG. 19 it being understood that the rear side is a mirror image thereof;

FIG. 23 is a bottom plan view of the housing of FIG. 19; and,

FIG. 24 is a top perspective view of the cleaner of FIG. 19 shown positioned on a pool cleaner body.

The broken line showing of a pool cleaner body in FIGS. 6, 12, 18 and 24 is for illustrative purposes only and forms no part of the claimed design.
